UNITED STATES PATENT OFFICE.

WALTER W. NASH, OF DOBY SPRINGS, OKLAHOMA.

TOY.

1,159,253.

Specification of Letters Patent.

Patented Nov. 2, 1915.

Application filed February 20, 1915. Serial No. 9,627.

To all whom it may concern:

Be it known that I, WALTER W. NASH, a citizen of the United States, residing at Doby Springs, in the county of Harper and 5 State of Oklahoma, have invented certain new and useful Improvements in Toys; and I do hereby declare the following to be a full, clear, and exact description of the invention, such as will enable others skilled in 10 the art to which it appertains to make and use the same.

This invention relates to wind propelled toys, and the primary object of the invention is to provide a toy embodying a wind 15 wheel, which operates representative figures of a man and a woman, giving the impression that the woman is rotating the wheel, and the man urging her on to greater efforts.

Another object of this invention is to provide a toy embodying a representative figure 20 of a woman, which has pivoted arms, legs and feet, for imparting a lifelike appearance upon the operation of the toy by the rotation of the wind wheel.

With the foregoing and other objects in 25 view this invention consists in such novel features of construction, combination and arrangement of parts as will be hereinafter more fully described, illustrated in the accompanying drawings and claimed.

In describing the invention in detail reference will be had to the accompanying drawings wherein like characters designate like or corresponding parts throughout the 35 several views, and in which:—

Figure 1 is a perspective view of the improved toy, Fig. 2 is a side elevation of the toy, showing parts thereof broken away, Fig. 3 is a view of the female representative 40 figure, and Fig. 4 is a view of the male representative figure.

Referring more particularly to the drawings, 1 designates a supporting platform of the toy, which is pivotally mounted upon 45 the upper reduced end 2 of an upstanding pin or supporting pole 3. The supporting platform 1 has a weather vane 4 secured thereto, so that it will be rotated upon the reduced end 2, for properly positioning the 50 toy for actuation by the current of a breeze or the wind.

The supporting platform 1 has an upstanding standard 5 secured thereto, which standard rotatably supports a crank shaft 6. The crank shaft 6 has a wind wheel 7 of the ordinary construction mounted upon one

end thereof, and it has its crank portion 8 positioned upon the opposite sides of the standard 5.

The crank portion 8 has arms 9 and 10 of 60 the representative figure 11 of a woman loosely connected thereto for permitting of rotation of the crank shaft independent of the arm. The arms 9 and 10 of the representative figure 11 are pivotally connected 65 to the torso 12 of the representative figure, as is clearly shown at 13. The torso 12 has legs 14 and 15 pivotally connected thereto, which legs are in turn pivotally connected to feet 16 and 17. The feet 16 and 17 are 70 secured to the supporting platform 1 in any suitable manner.

A representative figure 18 of a man is secured to the supporting platform 1 rearwardly of the representative figure 11, and 75 it has one leg 19 pivotally connected to the torso thereof. The foot 20, which is secured to the pivoted leg 19, is free from attachment to the supporting platform 1. The pivoted leg 19 of the representative figure 80 18 is connected to the torso 12 of the image 11 by a wire 21, so that when the torso 12 moves forwardly, as indicated in dotted lines in Fig. 2 of the drawing, the pivoted leg 19 will also move forwardly and 85 the foot 20 thereof will engage the torso 12 of the image 11, as is indicated in dotted lines in Fig. 2 of the drawing.

The legs 14 and 15 of the representative figure 11 are provided with shoulders 22 90 formed thereon, which shoulders engage the feet 16 and 17 and limit the forward movement of the legs 14 and 15 during the operation of the device.

In the operation of the improved toy: 95 The weather vane 4 will move the supporting base or platform 1 down upon its pivotal connection with the post 3, so that the current of the wind will properly strike the blades of the wind wheel 7, for rotating the 100 wind wheel. The rotation of the wind wheel 7 will rotate the crank shaft 6. The rotation of the crank shaft 6 will move the torso 12 of the image 11, upon its pivotal connection with the legs 14 and 15, causing 105 it to move into the position indicated in dotted lines in Fig. 2 of the drawing, and imparting an appearance or idea that the woman or representative figure 11 is rotating the crank shaft and consequently the 110 wheel 7. The downward pivotal movement of the torso 12 will move the pivoted leg

19 of the male representative figure 18 upwardly, causing the toe of the foot 20 to strike the representative figure 11, as is indicated in dotted lines in Fig. 2 of the drawing, creating the impression that the man is urging the woman to greater efforts.

From the foregoing description taken in connection with the accompanying drawings the advantages of construction and of 10 the method of operation of the improved toy will be readily apparent to those skilled in the art to which this invention appertains and, while in the foregoing description, the principle of the operation of this invention 15 has been described together with various features of construction, it is to be understood that certain minor features of construction, combination and arrangement of parts may be altered to suit practical conditions provided such alterations are comprehended within the scope of what is 20 claimed.

What is claimed is:—

1. A toy, a supporting base, a representative 25 human figure mounted upon said base including a torso, arms pivotally connected to said torso, legs secured to said base, said torso being pivotally connected to said legs, a second representative human figure carried by said supporting base rearwardly of said first named figure, said second named figure having a pivoted leg, means connecting said pivoted leg to said torso for moving the leg synchronously with movement 30 of the torso, and means connected to said pivoted arms for pivotally moving said torso.

2. In a toy, a supporting base, a wind 40 wheel, a crank shaft operatively connected to said wind wheel, a representative figure of a person carried by said supporting base, pivotally connected to its legs, said pivoted arms 45 being rotatably connected to said crank shaft for moving said torso upon its pivotal connection with the legs upon the rotation of said wind wheel, a second representative figure carried by said supporting base, said second named representative figure having a pivoted leg, said pivoted leg connected to said torso for pivotal movement upon the pivotal movement of said torso.

3. In a toy, a supporting base, a wind 50 wheel supported by said base, a crank shaft connected to said wind wheel, a represent-

ative figure of a woman having pivoted arms, a torso, legs pivotally connected to said torso, feet secured to said base, said legs being pivotally connected to said feet, 60 shoulders formed upon said legs for engaging said feet for limiting the pivotal movement of said legs, said pivoted arms being rotatably connected to said crank shaft for moving said torso upon its pivotal connection with said legs upon rotation of said wind wheel, a representative figure of a man carried by said supporting base and embodying a pivoted leg, a foot formed upon said pivoted leg, said pivoted leg being connected to said torso for pivotal movement upon pivotal movement of said torso for causing said foot to engage said torso upon the forward pivotal movement of the torso.

4. In a toy, a pivoted supporting base, a 75 wind wheel carried by said supporting base, a weather vane secured to said supporting base for moving it upon its pivotal support for positioning said wind wheel in line with a current of wind, a crank shaft operatively 80 connected to said wind wheel, a representative figure of a woman supported by said supporting base, said representative figure embodying a torso, legs pivotally connected to said torso, feet rigidly connected to said 85 supporting base, said legs being pivotally connected to said feet, shoulders formed upon said legs for limiting the forward pivotal movement of the legs, arms pivotally connected to said torso, said arms being rotatably connected to said crank shaft for moving said torso upon its pivotal connection with said legs upon rotation of the 90 wind wheel and crank shaft, a representative figure of a man carried by said supporting base and positioned rearwardly of 95 said first named representative figure, said representative figure of a man embodying legs, one of said legs being securely connected to said supporting base, the other of 100 said legs being pivotally connected to said representative figure, a rod connected to said pivotal leg and to said torso for moving said leg synchronously with the movement of said torso.

In testimony whereof I affix my signature in presence of two witnesses.

WALTER W. NASH.
